UNITED STATES PATENT OFFICE.

NORMAN A. PALMER, OF LOUISVILLE, KENTUCKY.

FOLDING-DOOR STRUCTURE.

1,246,314.

Specification of Letters Patent. Patented Nov. 13, 1917.

Application filed July 5, 1917. Serial No. 178,795.

To all whom it may concern:

Be it known that I, NORMAN A. PALMER, of Louisville, Jefferson county, Kentucky, have invented new and useful Improvements 5 in Folding-Door Structures, of which the following is a full and complete specification.

The object of my invention is to provide folding doors adapted for use in closing wide door-spaces, of such type that the folding door can readily be folded back out of the way, and that the operation of folding shall be easily done and with a minimum of interference with the furnishing of the room.

I am aware that folding doors made up of 15 a number of panels have been heretofore used, but the improvements hereinafter described and claimed, are, as I believe, novel.

Figure 1 represents a plan or top view of the door and the track by means of which 20 the door panels are supported and guided, parts of this track being left out, for convenience in getting the drawing on the sheet. In this drawing, the greater part of the door is shown folded back out of the 25 way. Fig. 2 is an elevation corresponding to Fig. 1, and showing the door panels in the same position as illustrated in Fig. 1. A part of the partition structure is shown cut away, so as to exhibit certain details 30 which would otherwise be hidden, and which are later referred to. Fig. 3 is a plan view of applicant's invention, showing the door extended to a point where the door opening is nearly closed, the track being cut away 35 in the middle portion to give a clearer view of the door and the small carriages which support the panels. Fig. 4 is a side view of one of the carriages used to support the panels, showing its relation to the track on 40 which it runs. Fig. 5 is a cross section at X—X of Fig. 4 showing the method by which the panels are suspended and guided. Fig. 6 is a detail view of small fending rollers inset in the panels.

45 Similar figures refer to similar parts throughout the views.

In the drawings, A and B represent opposite walls of the room or opposite door facings, the distance between the same representing the horizontal width of the door opening which is to be closed by the door-shutter. A multiplicity of door-sections or panels, 1, 2, 3, 4, 5, 6, 7, 8, 9, is provided, each panel except the innermost being preferably about as wide as an ordinary room door and nearly as tall as the opening which

is to be closed by the folding door. The panels are so hinged together on vertical edges that when completely extended, they form a door-shutter, adapted to close the entire opening, and when folded together with the panels parallel to each other form a compact mass against the wall A, extending out from the wall a distance equal to the combined thickness of the several panels. It will be noticed that the hinging is alternate, that is alternate joinings bend in opposite directions. The panel 1, nearest the wall A, is approximately half the width of the other panels, and is appropriately hinged to the wall A. In the form shown, the shutter formed by the panels is mainly supported by movable carriages or supports 17, which are adapted to support alternate panels at the centers of the tops thereof, and which are further adapted to move upon certain tracks 25 hereinafter described, the said tracks 25 also serving as guides, directing the motion of said carriages 17. Said movable supports or carriages 17, as illustrated, 80 are each composed of four wheels 20 and a central frame or body 19 having a vertical opening therein through which passes a supporting rod 21 enlarged at the top, so that said rod 21 is free to turn, but not to pass through said opening. A plate 23 is fixed to the upper portion of the door panels, and the said supporting rod 21 is bolted to said plate 23, so that the weight of the panel, or any other portions of the door, is mainly 85 carried by the supporting rod 21 and the carriage 17. It will be noticed that the construction permits the turning of the door panel about the axis of the rod 21, without turning the carriage 17. The rectangular 90 tube or pipe 10 has a slot in its lower portion running the length of the tube, shown in section in Fig. 5, the horizontal walls of the tube on either side of said slot, serving as tracks 25 on which the wheels 20 of the 95 carriage are adapted to run, the supporting rod 21 passing through the said slot. The fending roller 22 is provided, being confined to rotation around the axis of the rod 21 at such a point that it bears against one side or the other of the slot, being slightly less in diameter than said slot is wide. It is an idle roller, and tends to prevent binding, and to assist in directing the motion of the carriage 17, carrying the door panels.

100 The tube 10, the lower inner walls of which constitute the tracks 25 on which the

carriage 17 runs, is suspended by the hanger attached to a supporting joist 15 above, said hanger being fastened to the tube 10 by the strap 12. As is hereinafter described, the 5 tracks 25 and the tube 10 are curved at a part of their length, such curved portion being closer to the wall A, that is, to the wall to which the door is hinged, than to the wall or door-facing B.

10 Applicant's device avoids the waste of space necessarily involved with the type of folding door referred to, by making it possible for some parts of the door to be extended completely before other parts of the 15 door have changed their position at all. After the panels have been unfolded adjacent to the curved portion of the track, they can be slid forward, requiring no more space than the thickness of the door. This re- 20 sult is made possible by the curve in the track, as shown at 11. This curve is so formed and spaced that some of the panels may be unfolded, without moving other panels or folding other panels and some may 25 be folded, while the others remain in direct line.

In order to regulate the folding and unfolding of the panels, and to prevent any folding of panels in that portion of the 30 door space which is farthest away from the door facing A, to which the end panel is attached, fold-preventing members are provided extending from the wall B part way across the upper part of the door opening, and extending down far enough so that panels which have advanced far enough to tie between said members, are kept edge to edge, their corresponding surfaces lying in the same plane. Thus, folding or unfolding is confined to that portion of the width of the door space, which is adjacent to the inner or attached end of the door, which is hinged. Folding occurs only in that part of the door opening which is not affected by the fold-preventing members above referred to. As shown in the drawing, the fold-preventing members consist of two angle irons 13 and 14 attached to the tracks, extending down therefrom so that they are 50 on each side of the door panels when extended perpendicularly to the door facing A, thus forming flanges, extending part way across the upper part of the door opening, so as to prevent any folding of the panels 55 which are pulled out far enough to be in that part of the door space.

So-called "accordion" doors of the sliding type are common. It is usual to support such doors by carriages designed to support 60 alternate panels, and to furnish a track, running above the door opening, so that the door can be drawn back and forth. In this usual construction, the supporting carriages being attached at the centers of certain of 65 the panels, usually alternate panels, it is

necessary that as the door is extended each of the panels deviates by an equal angular distance from the general direction of the open door; that is, the whole door opens uniformly, like an accordion. This characteristic of the ordinary sliding folding door is a disadvantage, because it tends to make the door harder to handle, and more likely to bind, and also because the door when partly opened takes up a great deal of floor 75 space. The trouble is occasioned by the fact that the centers of the panels are confined to a straight line, so that when one moves, all of them being hinged together must move at the same time. Therefore, unless sufficient force is applied to set all the panels in motion at once, no motion occurs. As shown later, applicant's device is free from this objection, and responds to a gentler 80 force.

The curve is so formed and located that if all of the panels are folded back together against wall A parallel to each other, an operator, grasping the outer-most or free panel, is able to pull it out to the position 90 shown in Fig. 1, without changing the position, or exerting any force on any panels except the one which he is touching and the one next to it, the curve in the track permitting the carriage and consequently the center of the first panel, to get out of line with the centers of the other panels, and so unfold while others remain folded. If the operator continues to pull, beyond the position shown in Fig. 1, another panel will be moved, and the carriage attached to panel 7 as shown in the drawing will begin to follow the same course pursued by the carriage supporting the panel 9. When the operation is continued further, the outermost panel will assume a position perpendicular to the wall A, while the remaining panels will be in various angular positions. No change takes place in the position of the inner-most panel, until the process of extending the door has progressed a considerable degree. It is obvious that the curve is located with reference to the panel supports so that when the door is completely extended, none of the panel supports come to rest on the curved portion 115 of the track. When the door is closed, and it is desired to move the shutter back out of the way, the narrow panel is folded back first, and thereafter, the outermost panel is pushed back edgewise. When this is done, 120 folding occurs adjacent to the curve in the track, which guides the carriages so that gradually the panels are folded together at that part of the door-opening, until all are folded. To facilitate the easy operation of 125 the device, there are inset in the upper and inner corner of each panel small fending rollers, as shown in Fig. 6, with vertical axes, and of such dimensions that the circumference of the roller extends out on each 130

side a short distance, and comes opposite the fold preventing members previously referred to, tending to diminish friction between the panel and said members.

5 It is found by experiment that it requires less force to operate a door of this type, and that it can be operated with less tendency to stick or bind, than any other type. For this reason applicant's invention is particularly useful in cases where it is desired to operate a number of such doors simultaneously by mechanical means. My invention is not limited to the form of track here shown, nor to the specific embodiment illustrated herein.

10 I am aware that folding doors have been heretofore constructed, in which carriages have been provided, adapted to support the shutter, at certain joinings, and attached in such a way that when two carriages approach each other, the two sections, between the points of attachment of the two carriages, fold together, projecting outwardly from the track on which the carriages run, 15 but such a construction has serious disadvantages, not present in my device. It will be seen that in the process first above described, the door is thrown out of balance. It requires some kind of a stay or groove at the bottom in order to prevent the whole 20 structure from assuming an inclined position. In my device, there is practically no friction except that due to the weight of the door, and no groove is necessary at the bottom, because my device is at all times 25 perfectly balanced. Where a part of the door projects out in one direction from the track, without anything in the other direction to balance it, there is inevitably friction against the groove at the bottom, by reason of the 30 tendency of the door to balance itself and assume an inclined position.

35 I am also aware that doors have been constructed having a slot with a curve or bend at one end thereof, adjacent to the wall against which the door is to be folded, for the guidance of only one panel, that next to the jamb. It can be seen at once that the usefulness of such a structure is limited to 40 doors which are light enough so that the top support is not required at short intervals, or to doors which have a track or supports at the bottom. It will be seen that my device need not touch the floor or have any guide 45 or support at the floor at all, and permits the use of a support for every alternate panel. My device has positive guidance and direction at the point of support of alternate panels as they pass the location of 50 the curve, which is impossible in any structure in which the curve is located adjacent to the wall against which the folding occurs. It will be noticed that in my device the curve in the track does not extend to either 55 end but has straight end portions extending

in the same direction, with a curved portion intermediate thereof, the distance from the wall against which the door is to be folded to the beginning of the curved portion of the track is approximately equal to the aggregate thickness of all the panels, this being the preferred distance. However, if this approximate distance is preserved, a variation of one or two panel thicknesses would not necessarily render the device inoperable. 70 The curved portion of the track in my device is located at a part of the track which is traversed by all the carriages when the door is moved from a completely folded up position to a completely extended position 75 or the reverse.

80 I claim as new and desire to protect by Letters Patent the following:

1. In a folding door structure, a multiplicity of panels hinged together, alternate 85 joinings of which face in opposite directions, movable means for supporting certain of said panels, said supporting means being attached to panels supported thereby, approximately in the center of the top of said panels, 90 all in combination with a track in contact with said movable means, said track having two straight portions extending in approximately the same direction and an intermediate curved portion connecting said straight 95 portions.

2. In a folding door structure, designed when completely extended to close the door opening, a multiplicity of panels hinged together, so that alternate joinings open in opposite directions, carriages from which certain of said panels are suspended, each suspended panel being attached to a part of its carriage at approximately the middle part of the top of the panel, in combination with a 100 track in contact with said carriages, said track having two straight portions extending in the same direction, and a curved portion between and connecting said straight portions, the distance between the curved 105 portion and one edge of the door opening being approximately equal to the aggregate 110 thickness of the several panels.

3. In a folding door structure, adapted when extended to close a door opening, and when drawn back, to leave same open, a multiplicity of panels hinged at alternate vertical joinings, in opposite directions, means for movably supporting certain of said panels by attachment approximately at the 115 center of the top of the panels so supported, and means for causing said movable supporting means, when the panels are moved in closing the door opening or in opening same, to follow a path of which the beginning and 120 end portions are in the same directions and an intermediate portion changes direction.

4. In a folding door structure adapted to close a door opening, or leave same substantially open, according to the position of its 125 130

movable parts, a shutter composed of a multiplicity of panels joined by hinges, alternate panels being hinged in opposite directions, in combination with carriages attached approximately at the center of the top of certain panels, and a track on which said carriages are movable as the panels are folded or extended, said track being straight at the portions adjacent to each side of the door opening, but having a curve at a part thereof

which is traversed by all of the carriages, when the door is moved from a completely folded up position to a completely extended position, one straight portion of said track running in approximately the same direction as the other. 15
